FUEL CLEANING DEVICE FOR LIQUID FUELS

Filed Oct. 3, 1925

UNITED STATES PATENT OFFICE

BURT NEULON PIERCE, OF NEW YORK, N. Y.

FUEL-CLEANING DEVICE FOR LIQUID FUELS

Application filed October 3, 1925. Serial No. 60,326.

This invention relates to fuel feeding devices for motor vehicles and is an improvement on my application filed January 25, 1925, Serial Number 5,363, the object being to provide an oscillating filtering medium which can be oscillated so as to clean the foraminous surface in order to allow the fuel to pass readily therethrough.

Another object of my invention is to provide a fuel feeding device wherein a rotary drum having a foraminous surface is mounted in the head of the device in such a position that the fuel in its passage therethrough passes through the foraminous surface so as to remove all foreign matter therefrom.

Other and further objects and advantages of the invention will be hereinafter set forth and the novel features thereof defined by the appended claims.

In the drawings,

Figure 1 is a perspective view of a device showing it installed in connection with a vacuum fuel feeding system;

Figure 2 is a vertical section through the device, partly in elevation; and

Figure 3 is a section taken on line 3—3 of Figure 2.

In carrying out my invention, I employ a base 1 and a head 2, between which is disposed a rectangular glass tube 3 so as to form a visible feeding device. The rectangular glass tube is preferably seated on cork gaskets 4 arranged respectively in the base and head so as to form a gas-tight joint, the head and base being secured together by bolts A.

The base is provided with an inlet to which is connected a feed pipe 5 adapted to be connected to the main fuel tank, and the head is provided with an outlet which is connected by a pipe 6 to the vacuum tank of a vacuum fuel feeding system. The base is also provided with the usual drain plug 7, the particular construction so far described being substantially the same as shown in my above-referred to application.

In the embodiment of my invention as herein shown the head 2 is enlarged to form a chamber in which is mounted a filtering

drum composed of a hub 8 having discs 9 secured thereto between which is arranged a strip of foraminous material 10, preferably of wire gauze, the discs being notched as shown at 11, and the strip of foraminous material terminating at each side of the notch so as to form an opening from the inside of the drum which is adapted to align with the outlet of the head so that the fluid in passing through the drum will have a free outlet.

The head at each side is cut away to form a chamber 12 in which are arranged strips of felt 13, which contact with the periphery of the drum so as to prevent the fluid from passing up along each side of the periphery of the drum and said strips of felt form wipers which are adapted to clean the foraminated surface of any foreign matter which adheres thereto.

The hub 8 is secured on a shaft 14 by a pin 15, the shaft being mounted in suitable bearings formed in the head and having one of its ends extended outwardly as shown provided with a crank 16 which can be oscillated so as to oscillate the drum. The crank is adapted to engage the nuts of the bolts A so as to limit the movement in order to prevent the cut-away portion of the fabric from being turned into such a position that the fluid could pass through the device without going through the filtering medium and it will be seen that when the crank shaft is oscillated, the drum will be oscillated so as to move the foraminated surface over the wipers in order to clean the same whereby a filtering means is provided which can be readily cleaned by simply oscillating a crank.

The device is provided with the usual nozzle 17 through which the fluid in its passage to the vacuum tank passes and is discharged into the chamber of the device, the operation of the device being substantially the same as that disclosed in the patent issued to Benjamin F. Zimmerman, January 25, 1921, Number 1,366,760, wherein the fluid is caused to flow intermittently in order to collect the foreign matter and water before

it enters the vacuum tank of the fuel feeding system.

While I have shown certain details of construction, I do not wish to limit myself to any particular manner of mounting the drum and oscillating the same as my invention consists broadly in providing an oscillating filtering member mounted in the head of the device in such a position that the fluid in its passage through the device is caused to pass through the foraminated surface, which surface can be readily cleaned by oscillating the same over the wipers, which not only performs the function of wipers but prevents the fluid from passing around the periphery of the filtering member and in the drawing I have shown a clearance above the drum in order to allow the fluid which passes into the drum to readily pass out through the outlet.

From the foregoing description it will be seen that I have provided a fuel feeding device for motor vehicles, especially adapted to be used in connection with a vacuum fuel feeding system wherein an oscillating filtering means is mounted in the outlet of the device in such a manner that the filtering cloth through which the fluid passes can be kept clean by simply oscillating a small crank arm mounted on the top of the device.

While in the drawing I have shown the filtering medium located in the head, I do not wish to limit myself to the use of the filtering medium of this particular character located at any particular point, as I am aware that the filtering medium can be placed at other points within the device so as to accomplish the desired result.

What I claim is:—

1. In a fuel feeding system for feeding fuel from a low level tank to a charge forming device, of a receptacle disposed in the feed line pipe between said tank and said charge forming device, said receptacle having an inlet at its bottom and an outlet at its top, a drum mounted in the upper end of said receptacle having a foraminous periphery cut away to form an outlet, means for oscillating said drum and wipers disposed to engage said foraminated surface for removing the foreign matter therefrom.

2. A device of the kind described comprising a base and a head having a rectangular glass tube secured between the same to form a chamber, said head being provided with a chamber, a drum mounted in said chamber having a foraminated periphery cut away to form an outlet, said drum being carried by a shaft mounted in said head and having a crank arm secured to one end thereof and wipers disposed at each side of said drum adapted to engage the periphery of said drum for removing foreign matter therefrom.

3. A fuel filterer and indicator for fuel feeding systems comprising a receptacle having transparent side walls, said receptacle having a demountable head provided with a chamber, a filtering drum mounted in said head comprising a hub having a pair of discs secured thereto between which is secured a strip of foraminated material terminating short of its end thereof to form an outlet opening, a shaft upon which said hub is mounted, a crank arm carried by said hub for oscillating said drum and strips of felt arranged at each side of the periphery of said drum and contacting with the foraminated surface thereof for cleaning the foraminated surface of foreign matter when said drum is oscillated.

In testimony whereof I hereunto affix my signature.
